TELEVISION ANTENNA

Marvin P. Middlemark, Rego Park, N.Y.
(P.O. 99-05 63rd Drive, New York, N.Y.)

Filed Sept. 14, 1961, Ser. No. 66,717

Term of patent 14 years

(Cl. D26—14)

FIG. 1 is a front perspective view of a television antenna, showing my new design;

FIG. 2 is a side view thereof in elevation;
FIG. 3 is a top plan view thereof.

I claim:

The ornamental design for a television antenna, substantially as shown.
